UNITED STATES PATENT OFFICE.

ARTHUR PRIDDLE, OF SAN FRANCISCO, CALIFORNIA.

REINFORCING-BAR FOR CONCRETE STRUCTURES.

No. 870,129.

Specification of Letters Patent.

Patented Nov. 5, 1907.

Application filed September 20, 1906. Serial No. 335,391.

To all whom it may concern:

Be it known that I, ARTHUR PRIDDLE, a citizen of the United States, residing at San Francisco, in the county of San Francisco and State of California, have 5 invented certain new and useful Improvements in Reinforcing-Bars for Concrete Structures; and I do declare the following to be a full, clear, and exact description of the invention, such as will enable others skilled in the art to which it appertains to make and 10 use the same.

This invention relates to improvements in devices for reinforcing concrete structures, and it consists of the novel construction, combination and arrangement of parts hereinafter described and claimed.

15 The object of the invention is to provide a simple and inexpensive tension bar or element which may be embedded or anchored in a concrete structure of any description to effectively strengthen and reinforce the same.

20 The above and other objects, which will appear as the nature of the invention is better understood, are accomplished by the construction herein described and illustrated by the accompanying drawing, in which,—

25 Figure 1 is a side elevation of a portion of one form of the improved reinforcing bar or member; Fig. 2 is a sectional perspective view of the same; Fig. 3 is a view similar to Fig. 1, of a slightly modified form of the invention; and Fig. 4 is a transverse sectional view 30 taken on a plane indicated by the line 4—4 in Fig. 3.

In the practice of the invention, I preferably employ a flat metallic bar 1 of rectangular form in cross section and by suitable means slit the same longitudinally at points suitably distant apart. I then stamp or bend 35

by suitable means, the edges of the slits or openings 2 outwardly to form right angular anchoring flanges or ribs 3. These flanges or ribs 3 may be bent outwardly in either direction at right angles to the plane of the bar and they are preferably curved and tapered longitudinally so as to leave the slit or opening 2 of substantially elliptical form. The slits or openings 2 may be 40 of any desired size and arranged at any desired distance apart and they do not in any way weaken the bar since its sectional area is not reduced. On the

45 contrary, they add strength and rigidity to the bar because they form arches, two of which are formed by the elliptical curvature that corresponds with the walls of the opening, which will strengthen the bar in the plane of its width, or widest section, and the

other arches will be formed by the curvature of the 50 edges of the flanges which will add strength to the bar transversely, or across its shortest section. The slits 2 and the flanges 3 may be cut and stamped in the flat bar 1 without heating the same but in some cases when the bar is very heavy and of other forms than that shown 55 it may be necessary to heat the same to permit the slits or openings to be formed therein. If desired, the bar 1 may be twisted spirally at suitable intervals, as shown in Figs. 3 and 4. The twist helps the bar and concrete to mutually anchor each other in the structure, 60 thereby strengthening the latter to a greater extent than would a straight bar. In other words, the changing shape of the twist bar serves to conserve the strength of the concrete and does not tend to weaken it as does a straight or flat bar when set upon its edge, the flat 65 bar in such case forms in a sense a cutting edge when under severe strain, and hence tends to weaken the concrete. This objection is overcome in the twist bar, as will be understood.

In use, the bar or member is embedded in concrete 70 structures, such as floors, arches, beams, girders, foundations, walls, columns, piers and similar structures of concrete or other plastic material. The bar may be arranged in concrete in any shape, singly or compound, at any angle, and at any suitable distances 75 apart, and if desired, the bars may be laid at right angles in the structure and tied together with suitable fasteners; or the bars may be woven together, forming a fabric where the necessity requires the placing of considerable material of this nature in the structure. 80 The weaving may be accomplished by stringing the bars through the perforations and tying them in as desired.

From the foregoing description, taken in connection with the accompanying drawing, the construction 85 and operation of the invention will be readily understood without requiring a more extended explanation.

Various changes in the form, proportion and the minor details of construction may be resorted to without departing from the principle or sacrificing any 90 of the advantages of this invention, as defined by the appended claims.

Having described my invention, what I claim as new and desire to secure by Letters-Patent is,—

1. A reinforcing element for concrete structures, comprising a flat metallic bar having slits formed longitudinally therein, and having the portions of the bar adjacent to said slits bent laterally in opposite directions at right angles to the plane of the bar, whereby flanged elliptical

openings are formed, and the base or bottom of each flange or bent portion is in the form of an arch lengthwise of the bar, and the outer edge is in the form of an arch at right angles to the plane of the bar.

- 5 2. A flat, spiral, twisted reinforcing bar having an opening extending longitudinally thereof, said opening having oppositely curved sides, each formed by a longitudinally-curved lip projecting laterally from the general plane of that portion of the bar in which said opening is

located, said lips being broadened at their centers and 10 narrowed toward their ends, and respectively extending from opposite sides of the bar.

In testimony whereof I have hereunto set my hand in presence of two subscribing witnesses.

ARTHUR PRIDDLE.
